(57) **CLAIM**

The ornamental design for a leaning stand for telecom transmitters as shown and described.

DESCRIPTION

FIG. 1 is a top perspective view of a leaning stand for telecom transmitters;

FIG. 2 is a bottom perspective view thereof;

FIG. 3 is a front view thereof;

FIG. 4 is a rear view thereof;

FIG. 5 is a bottom view thereof;

FIG. 6 is a top view thereof; and,

FIG. 7 is a side view thereof, the opposite side being a mirror image.

The broken lines in the drawings illustrate portions of the leaning stand for telecom transmitters, which form no part of the claimed design.
